UNITED STATES PATENT OFFICE.

WILLIAM A. JAMESON, OF NIAGARA FALLS, NEW YORK.

DESIGN FOR A SPOON, FORK, OR SIMILAR ARTICLE.

42,756.

Specification for Design.

Patented July 9, 1912.

Application filed May 24, 1912. Serial No. 699,568. Term of patent 7 years.

To all whom it may concern:

Be it known that I, WILLIAM A. JAMESON, a citizen of the United States, residing at Niagara Falls, in the county of Niagara and State of New York, have invented a new, original, and ornamental Design for a Spoon, Fork, or Similar Article, of which the following is a specification, reference being had to the accompanying drawing, forming part thereof.

The figure is an obverse view of a spoon, fork or similar article showing my new design.

I claim:

The ornamental design for a spoon, fork or similar article as shown.

WILLIAM A. JAMESON.

Witnesses:

HAZEL B. FENWICK,
B. J. MOSIER.

Copies of this patent may be obtained for five cents each, by addressing the "Commissioner of Patents, Washington, D. C."
